US00D937209S

(12) **United States Design Patent** (10) **Patent No.:** **US D937,209 S**
Luo (45) **Date of Patent:** **** Nov. 30, 2021**

(54) **MULTI-PORT SMART CHARGER**

(71) Applicant: **SHENZHEN SENRUI TECHNOLOGY CO., LTD.**, Shenzhen (CN)

(72) Inventor: **Xiaoxia Luo**, Shenzhen (CN)

(73) Assignee: **SHENZHEN SENRUI TECHNOLOGY CO., LTD.**, Shenzhen (CN)

(**) Term: **15 Years**

(21) Appl. No.: **29/767,979**

(22) Filed: **Jan. 27, 2021**

(51) **LOC (13) Cl.** **13-02**

(52) **U.S. Cl.**

USPC **D13/108**

(58) **Field of Classification Search**

USPC D13/103, 107-110, 118-119, 184, 199; D14/251, 253, 432, 434, 447; D6/682

Primary Examiner — Rosemary K Tarcza

(57) **CLAIM**

The ornamental design for a multi-port smart charger, as shown and described.

DESCRIPTION

FIG. 1 is a perspective view of a multi-port smart charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the multi-port smart charger that form no part of the claimed design.

1 Claim, 8 Drawing Sheets
